UNITED STATES PATENT OFFICE.

AUGUSTE A. GOUBERT, OF JERSEY CITY, NEW JERSEY.

AUTOMATIC DISCHARGING APPARATUS FOR BONE-BLACK KILNS, &c.

SPECIFICATION forming part of Letters Patent No. 254,474, dated March 7, 1882.

Application filed July 9, 1881. (No model.)

To all whom it may concern:

Be it known that I, AUGUSTE A. GOUBERT, of Jersey City, State of New Jersey, have invented a new and useful Improvement in Automatic Discharging Apparatus for Bone-Black Kilns, &c., of which the following is a specification, reference being had to the accompanying drawings.

My invention relates to that class of apparatus used for discharging in uniform quantities granular or doughy materials from pipes, bins, or tanks; but I will describe it more particularly in its application to certain kilns for the revivification of bone-black or animal charcoal, in which vertical retorts are made to revolve upon their own axis. On these kilns the apparatus heretofore used for discharging the retorts has been that described in Letters Patent No. 150,821, granted to Buchanan and Vickers, dated May 12, 1874.

My improvement, as applied to these kilns, consists in one or more arms or blades secured to the revolving shaft or spindle and inclined backward from the direction of motion, and which as they revolve push out the coal over the edge of a stationary disk on which it is constantly resting.

In the drawings, Figure 1 is a perspective elevation of my apparatus. Fig. 2 shows the apparatus with the upper part cut off, and illustrates the mode in which the material is forced over the edge of the disk. Fig. 3 is a vertical section through a bone-black kiln, of which the retorts are revolved upon their own axis through the shaft or spindle C, showing my apparatus in connection with such a kiln.

A is a worm-wheel, keyed on the spindle C, and through it imparting motion to the vertical retort, and also to the whole apparatus.

B B are sheet-iron pipes called "coolers," in which the charcoal is cooled after it leaves the retort and before it comes in contact with the air.

D is a disk on which the column of charcoal is resting.

E E are wings or arms bent backward from

the direction of motion and moving with the spindle C.

The operation of the apparatus is as follows: The charcoal contained in the coolers B B falls through the wheel A upon the disk D and spreads out around the rim of the wheel or its projection until it forms an angle of about thirty-five degrees, and there remains stationary. Now, if we revolve the apparatus in the direction shown by the arrow, the arms E E act as rotating wedges and push out the coal toward the edge of the disk, over which it falls continuously as long as the machine rotates.

The arms E E are shown on the drawings as being curved; but they may be straight with similar effect.

Modifications of this apparatus can of course be made to suit various purposes, and the arms, if revolved in the opposite direction, could be made to discharge at the center of the disk.

Instead of the shaft C being inside of the arms E E, it may be enlarged considerably, so as to form a pipe, and the arms E be fastened to that pipe on the inside. It would be, notwithstanding, but a modification of my invention.

The wheel and coolers are merely shown so as to illustrate one application of my invention, but are not essential parts of the apparatus.

I claim as my invention—

1. In an automatic discharging apparatus, the wings or arms E E, bent backward from the direction of motion, in combination with the disk D and the revolving shaft C, substantially as herein specified.

2. The arms E E, substantially as herein described, in combination with the wheel A, the disk D, and the coolers B B of a revolving charcoal-kiln.

In witness whereof I have hereunto set my hand, this 8th day of July, 1881, in the presence of two subscribing witnesses.

AUGUSTE A. GOUBERT.

Witnesses:

D. B. PRESTON,
ARTHUR KRAUSE.
